UNITED STATES PATENT OFFICE.

SYDNEY I. FRESCOTT, OF NEW YORK, N. Y.

INTERNAL-COMBUSTION ENGINE.

1,274,777.

Specification of Letters Patent.

Patented Aug. 6, 1918.

Application filed October 13, 1916. Serial No. 125,361.

To all whom it may concern:

Be it known that I, SYDNEY I. FRESCOTT, a citizen of the United States, residing at New York, county of New York, and State of New York, have invented a new and useful Improvement in Internal-Combustion Engines, of which the following is a specification.

This invention relates to an improvement 10 in internal combustion engines, particularly to those adapted for use as power plants for motor cars.

The principal object of the invention is the production of an engine embodying the 15 main advantageous features of engines of the two-stroke cycle and those of the four-stroke cycle, simplifying and otherwise improving them in the process of embodiment, but without importing the distinct disadvantages inherent in each. Another object is the 20 production of an engine in which the cycle of operation may be changed at will while the engine is running to convert it from a two-stroke cycle to a four-stroke 25 cycle engine, or vice versa.

In car starting, hill climbing, or heavy going through mud or sand, great power and frequent power impulses are highly desirable. Another object, therefore, is the production 30 of an engine so arranged that it operates on the two-stroke cycle at such times, developing its maximum power by way of frequent forceful power impulses rather than by way of a multiplicity of smaller cylinders or excessive speed, although the engine may have as many cylinders as desired 35 and may be run at high speeds.

During the greater part of the time a motor car engine is running, it develops power 40 far below its maximum because when the car is running over average roads and carrying average loads at any speed below maximum, great power and frequent power impulses are unnecessary. The power so developed 45 may be termed normal working power. Another object of the invention, therefore, is the provision of means whereby the cycle of operation of the engine may be changed at such time from a two-stroke 50 cycle to a modified four-stroke cycle, thus reducing the number of power impulses with respect to the engine revolutions when frequent impulses are not needed, and thereby creating a substantial reserve power, 55 held inert by reason of the temporarily sus-

pended two-stroke cycle but always available for instant use by simply re-changing the cycle of operation.

Another object of the invention is the production of throttle controls operative 60 separately for changing the engine cycle of operation and operative separately or together for varying the volume of fuel delivered to the engine. Another object is the production of a device whereby the engine 65 is adapted to develop two different powers on two different cycles of operation in order that car starting, most hill climbing, and most heavy going may be accomplished by simple throttle control manipulation and 70 without gear changing, thus making possible simplification of change gear mechanism. Another object is the production of an engine adapted when operating on one cycle to develop normal working power 75 through the agency of a small, light, non-expensive and highly efficient structure, and to develop greatly increased power when operating on another cycle, without any structural changes whatsoever. 80

With these and other objects not specifically mentioned in view, the invention consists in certain parts, constructions and combinations which will be hereinafter fully described and then specifically set forth in 85 the claims hereunto appended.

In the accompanying drawings which form a part of this specification and in which like characters of reference indicate the same or like parts, Figure 1 is a sectional elevation of a device constructed in accordance with the invention; Fig. 2 is a detail elevation, partly in section, of the throttle controls used in connection with the structure shown in Fig. 1; and Figs. 3, 4 90 and 5 are fragmentary views of the intake valves and chambers diagrammatically illustrating various positions of the same during the operation of the structure shown in Fig. 1. 100

In carrying the invention into effect, there is provided an internal combustion engine, and means for changing its cycle of operation while running. In the best constructions, fuel controlling means are used for 105 this purpose. There is further provided an engine adapted to develop normal working power when running on one cycle, and maximum power when running on another cycle. In the best constructions, the normal work- 110

ing power is developed when the engine is running on a modified four-stroke cycle, and maximum power is developed when the engine is running on a two-stroke cycle. There is further provided a source of fuel supply for the engine, and means for selectively controlling the transfer of fuel therefrom to the engine in accordance with successive or separated piston cycles. In the best constructions, independent sources of fuel supply and independent controls therefor are employed.

There is further provided throttle controlled means for effecting changes in the engine cycles of operation. In the best constructions, operative connections and a pair of throttle controls mounted in juxtaposition are used for this purpose. There is further provided an engine cylinder having both ends closed, a piston working within the cylinder and dividing it into a combustion chamber and an induction chamber, a source of fuel supply, and means for selectively controlling transfer of fuel from the source of supply to the induction chamber in accordance with successive or separated piston cycles. In the best constructions, this means includes a pair of rotary valves and independent throttle controls coöperative therewith. There is further provided a by-pass in the cylinder wall and adapted to open communication between the induction chamber and the combustion chamber only at the outer end of the piston movement. In the best constructions, this by-pass includes a chamber formed outside the outer end of the cylinder and a plurality of radial ports leading therefrom to the interior of the cylinder, the construction being such that the fuel is forced by its own pressure into the combustion chamber in a plurality of streams flowing at right angles to the axis of the cylinder and converging at the cylinder axis, then rising in the cylinder and driving the burnt fuel before it toward the inner end of the cylinder. There is also provided an exhaust port at the inner end of the cylinder so that the incoming fresh fuel need travel only the length of the cylinder to completely fill the same, as distinguished from the double distance it has to travel in engines having the exhaust port in the cylinder wall nearly opposite the intake port. In the best constructions, this port is located in the center of the cylinder head and is controlled by a mechanically operated puppet valve. There is further provided means for compressing the fuel to a higher degree than heretofore practised before its introduction into the combustion chamber in order that its own pressure will positively drive it from the induction chamber to the combustion chamber well within the limited time available when the engine is running at high speed. All of the above

elements, and others not specifically mentioned, may be varied in construction within wide limits.

The device selected to illustrate the invention is but one of many possible concrete embodiments of the same. The invention, therefore, is not to be restricted to the precise details of the structure shown and described. Furthermore, certain parts of the invention are capable of use independent of other parts, and such independent use is contemplated.

Referring to the drawings, 1 indicates the upper part of a crank case casing. Rabbeted into the top of the casing 1 is an outer cylinder head 2 which is provided with a stuffing box 3 of well known construction and operation. Mounted to reciprocate within the casing 1, which is or may be cylindrical in form below each cylinder, is a cross head 4 having suitable bosses not shown but of well known construction for supporting a wrist pin 5. On this wrist pin is mounted the forked end 6 of a piston rod 7 which projects through and reciprocates within the stuffing box 3. Journaled upon the wrist pin 5 is a connecting rod 8 which is also journaled upon the crank of the engine crank shaft not shown but well known in the art.

The cylinder head 2 is also piloted in the outer end of a cylinder 9, and serves not only to close the outer end of the cylinder but to keep it in accurate alinement with the bore of the casing 1. The inner end of the piston rod 7 is tapered at 10 and held to a spider 11 by means of a nut 12. Threaded into this spider is a piston head 13, and accidental displacement of the same is prevented by means of a tapered set screw 14. Piston rings 15 of well known construction are provided and lie between the piston head and spider flanges. The inner cylinder head 16 is cast integrally with the cylinder, although it is to be understood that it may be formed of a separate casting if preferred. The piston reciprocates within the cylinder, and it is to be understood that it completes what is termed herein a piston cycle when it has moved from its uppermost position, as shown in full lines in Fig. 1, to its lowermost position, as shown in dotted lines in the same figure, and back again. The cylinder and its inner head are inclosed within a water jacket 17 of well known construction. It may be here remarked that although the drawing shows only one cylinder, a plurality may and in most installations will be employed; and when a plurality of cylinders are employed their construction will be like that shown, and the water jacket will be extended to inclose all of them.

Outside of the outer end of the cylinder, or each cylinder, and preferably surround-

ing the same, is a cylinder chamber 18. Each cylinder chamber is provided with a plurality of radial ports 19 arranged symmetrically about the cylinder wall and establishing open communication between the cylinder chamber 18 and the interior of the cylinder. The purpose of these radial ports will be hereinafter described.

Beyond the cylinder chamber and oppositely disposed with respect thereto are two valve chambers 20 and 21 in which valves 22 and 23 are respectively arranged to rotate continuously in the direction of the arrows, although they may be designed to rotate differently. The valve chamber 20 is provided with a port 24 leading therefrom to the cylinder chamber 18. Similarly, the valve chamber 21 is provided with a port 25 also leading to the cylinder chamber 18. The valve 22 is provided with a channel 26 arranged to open the port 24 at proper intervals. Similarly, the valve 23 is provided with a channel 27 arranged to open the port 25 at proper intervals. The valve chamber 20 is further provided with a port 28 leading to a manifold 29. Similarly, the valve chamber 21 is provided with a port 30 leading to a manifold 31. Fuel for the manifold 29 comes from a carbureter indicated at 32, this carbureter being provided with a throttle operated by means of a throttle lever 33. Similarly, fuel for the manifold 31 comes from a carbureter indicated at 34, this carbureter being provided with a throttle operated by means of a throttle lever 35. The particular construction of the carbureters lies wholly outside of the present invention and a detailed description thereof is omitted herefrom in the interest of brevity and clearness. The valves 22 and 23 are rotated at half engine speed so that they will alternately control admission of fuel from the two manifolds to the outer part of the cylinder below the piston. It may be here

remarked that the piston serves to divide the cylinder into an induction chamber, that part below the piston, and a combustion chamber, that part above the piston. The particular construction of the mechanism used for driving the valves 22 and 23 lies wholly outside the present invention and therefore a detailed description of the same is omitted herefrom in the interest of brevity and clearness. It is sufficient for present purposes to say that they are driven at half engine speed and therefore alternately open the ports 24 and 25, or in accordance with alternate piston cycles.

From what has been said, and by an inspection of Fig. 1, it will be readily understood that fuel inspired in the induction chamber and cylinder chamber 18, coming from either carbureter and manifold, will be compressed between the lower side of the piston and the lower cylinder head 2 as the

piston travels downward. It will also be readily understood that this compressed fuel will be stored as compression progresses within the induction chamber and cylinder chamber 18 until the piston reaches a position where its upper edge uncovers the radial ports 19. The induction chamber and cylinder chamber 18 are so proportioned that the fuel will be compressed to a considerably higher degree than is customary in two-stroke cycle engines, and no leak can occur because of the action of the stuffing box 2 and close fit of the valves 22 and 23. It will therefore be readily understood that when the piston reaches the position where it begins to uncover the radial ports 19, the fuel will be driven by its own relatively high pressure into the combustion chamber at high speed and that when so driven it will pass into the combustion chamber in a plurality of streams converging at the axis of the cylinder, thus causing the inflowing fuel to rise in a mass in the cylinder, driving the burnt fuel before it.

In order to provide means for emptying the cylinder of burnt fuel in such a way as to avoid impeding the inflow of the fresh fuel, and to avoid loss of fresh fuel, the cylinder upper head 16 is provided with an exhaust port 36 which is large and located at the center of the cylinder head. This port is controlled by means of a puppet valve 37 having a stem 38 arranged to reciprocate within a bush 39 provided with a large flange 40 resting upon the top wall of the water jacket 17 above the exhaust conduit 41, this conduit being in open communication with the exhaust port 36. The upper end of the valve stem 38 carries a spring retainer 42 which is held in place by means of a retaining lock 43. A spring 44 in engagement with the retainer 42 and the flange 40 serves to normally hold the valve 37 in closed position.

Mounted in suitable bearings in the cylinder casting a little distance from the valve stem 38 is a rotating cam shaft 45 which rotates at engine speed so that the exhaust valve is opened at the proper time once during each piston cycle, or in other words once during each engine revolution. Engaging this cam shaft is a rocker lever 46-47 which is fulcrumed on a bar or pivot 48 suitably mounted in the cylinder casting. The arm 47 of the rocker lever 46-47 is provided with an adjusting screw 49 of well known construction and operation. The upper part of the cylinder casting is closed by an oil tight cover 50, so that the exhaust valve operating mechanism may be run in a bath of oil. The construction of the particular mechanism used for driving the cam shaft 45 lies wholly outside the present invention and a description thereof is therefore omitted in the interest of brevity and clearness.

An aperture 51 leading to the interior of the combustion chamber is provided, and in this aperture a spark plug may be secured.

- There is further provided a pair of throttle controls by means of which admission of fuel from the manifolds 29 and 31 may be controlled, either separately or together, for purposes hereinbefore mentioned. These throttle controls consist in levers 52 and 53 mounted in juxtaposition or one over the other in convenient position for manipulation together or separately. The control lever 52 is provided with a lug 54 engaging a semicircular sector 55. Similarly, the throttle control 53 is provided with a similar lug 56 also engaging the sector 55. The throttle control 52 is secured to a stem 57 and the throttle control 53 is similarly secured to a concentric hollow stem 58. These stems may be mounted on the steering post of the car in connection with which the engine is used, or may if preferred be mounted in any other convenient position. The stems 57 and 58 are connected by means of well known mechanism not shown, the one with the throttle lever 33 and the other with the throttle lever 35. The particular construction of these connections will necessarily be varied in accordance with different installations, and in any case they lie outside the present invention. Specific description of such connections is therefore omitted in the interest of brevity and clearness.
- The operation of the engine is as follows; and in describing its operation it will be first assumed that the parts are in the position shown in Fig. 1, and that the engine is installed in a motor car and is running idly or out of gear with the driving axle, both throttle controls and both carbureter throttles being open equally. The piston has reached the uppermost point of its movement and fuel is now flowing by its own momentum through the manifold port 28, the valve channel 26, and the valve chamber port 24 into the induction chamber and cylinder chamber 18. The valve chamber port 25 is closed at this time by the valve 23. When the piston has reached a point 20 degrees beyond upper dead center, the valve 22 closes the port 24 and fuel compression within the induction chamber begins. There is no escape for the fuel imprisoned within the induction chamber and therefore compression continues without danger of loss as the piston descends. When the piston reaches a point about 50 degrees ahead of lower dead center, the exhaust port 36 is opened and the burnt fuel begins its outward movement, forced by its own pressure. When the piston reaches the position where it begins to uncover the radial ports 19, the pressure in the combustion chamber has been reduced by the exhausting of the burnt fuel to about atmospheric pressure. As soon

as the piston begins to uncover the radial ports 19, the fresh fuel begins to flow, under the influence of its own relatively high pressure, in a plurality of streams radially inwardly and converging at the axis of the cylinder above the piston. The fuel contained in these streams expands in all directions possible as soon as it passes through the radial ports into the combustion chamber. It rushes radially inward toward the axis of the cylinder and at the same time expands laterally toward contiguous streams and upwardly toward the cylinder head. The effective result is the rapid formation of a stratum of fresh fuel occupying the lower part of the combustion chamber below the burnt fuel not then fully exhausted from said chamber. This stratum of fresh fuel rapidly builds up in depth as the fuel continues to rush in through the radial ports, and in so doing drives the remaining burnt fuel above it out through the exhaust port at corresponding high speed. It may be here remarked that since the fresh fuel has to travel only the length of the cylinder to completely fill the combustion chamber, a higher engine speed is attainable than when the exhaust port is located in the cylinder wall and the fresh fuel must travel both up and down the combustion chamber before the same can be completely filled. It may be noted that the displacement of the induction chamber is slightly less than the displacement of the combustion chamber. This is due to the presence therein of the piston rod. For this reason, the exhaust port 36 is kept open a little longer than would otherwise be necessary so that all of the burnt fuel is expelled from the combustion chamber before the exhaust port closes. This slight loss in combustion chamber displacement is compensated for by making the combustion chamber clearance slightly smaller. Compression for ignition occurs in the combustion chamber as the piston travels upwardly or toward the cylinder head 16.

When the piston reaches its lowermost position, the position of the valves 22 and 23 will be as shown in Fig. 3. It will be noted that the valve chamber port 24 is then closed and the valve chamber port 25 is about to open. When the piston reaches a position to cut off the radial ports 19, the valve chamber port 25 begins to open and a fresh charge of fuel is inspired therethrough from the carbureter 34 and manifold 31. This action continues until the piston passes upper dead center 20 degrees at which time it closes. Fig. 4 shows the valves 22 and 23 in the position they occupy when the piston is at upper dead center. The piston now descends under the force of the explosion in the combustion chamber and a fresh charge of fuel is compressed in the induction chamber. On this down stroke, as be-

fore, the exhaust port 36 begins to open at about 50 degrees ahead of lower dead center, and when the radial ports are uncovered transfer of fresh fuel from the induction chamber to the combustion chamber occurs as before. By an inspection of Fig. 5, it will be noted that while at this time the valve chamber port 24 is open, this opening is without effect because the manifold port 28 is still closed and does not open until the piston has traveled upwardly a distance sufficient to close the radial ports 19. This action, which is on a true two-stroke cycle, continues as long as both throttle controls are caused to hold both carbureter throttles open. It will of course be readily understood that by simultaneous manipulation of both throttle controls the volume of fuel delivered to the engine may be readily controlled.

Assuming now that the engine has been clutched to the driving mechanism of the car and that the car is running under conditions requiring only normal working power: The engine cycle of operation may now be changed without altering its speed, and this may be done by throttle control manipulation. Either of the throttle controls may be operated to close the carbureter throttle actuated by it, and the other throttle control operated to open the carbureter throttle actuated by it a little more. Assuming that the throttle control 53 is the one operated to close the throttle of the carbureter 34 actuated by it: The closure of the throttle of the carbureter 34 throws the manifold 31 out of action as a source of fuel supply, leaving only the carbureter 32 and manifold 29 in action as a source of fuel supply. The valve 22 will continue its function of controlling flow of fuel from the manifold 29 through the valve channel 26 and the valve chamber port 24 to the induction chamber and cylinder chamber 18, while although the valve 23 will continue to open the valve chamber port 25 at regular intervals, this opening will be without power effect because there will be no fuel in the manifold 31 to be inspired into the induction chamber and cylinder chamber 18 while the valve chamber port 25 is open. The effective result is that the engine will inspire a fresh charge of fuel only in accordance with separated or alternate piston cycles, or in other words once every other engine revolution, just half as often as before. The two-stroke cycle of operation has now been interrupted and the engine is now running on a different cycle of operation, a power impulse occurring every fourth piston stroke as in an ordinary four-stroke cycle of operation. This cycle is herein termed a modified four-stroke cycle because although the power impulses are the same, the method of obtaining them is different from that of an ordinary four-

stroke cycle engine. The throttle control 52 may now be manipulated alone to control the volume of fuel delivered to the engine operating on this modified four-stroke cycle, precisely as an ordinary throttle control is manipulated. It may be here remarked that any of the pedal actuated accelerator mechanisms well known in the art may be used in connection with one or both of the throttle controls.

The closure of one carbureter as a source of fuel supply establishes a reserve source of fuel supply which at any desired time may be brought into action by means of its throttle control to augment the normal working power.

Assuming now that the car is running along with its engine operating on this modified four-stroke cycle, the throttle being wide open so that the engine is developing its full normal working power, and a hill is reached: More power is needed and must be applied or gears will have to be shifted to gain power mechanically. Under these circumstances, the driver ignores his gears and again throws the carbureter 34 and manifold 31 into operation, thereby converting the engine cycle of operation into a two-stroke cycle, thus increasing the power by doubling the number of power impulses. When the top of the hill is reached, he again cuts out the carbureter 34 and the engine returns to its former modified four-stroke cycle of operation. On a heavy road, through deep mud or sand, a like change of cycle of operation may be resorted to; and also in starting. Since two powers are available without gear shifting, one gear shift will provide four powers which is enough to meet all contingencies, and accordingly the change gear mechanism may be materially simplified.

It will be readily understood that since the additional power derived from a change of cycle of operation from the modified four-stroke cycle to a two-stroke cycle does not involve additional cylinder displacement, the engine need be only large enough to develop the normal working power when operating on the modified four-stroke cycle, thus effecting a material saving in initial cost, in cost of maintenance, in weight and inefficiency.

Where greater power for a given bore of engine is considered of more importance than economy of installation and operation, the bore may be made the same; and in this case the reserve power derived from the change of cycle of operation from the modified four-stroke to the two-stroke cycle will be a clear power gain.

Where both greater power and economy is desired, the engine may be somewhat smaller than present practice and yet develop more power.

What is claimed is:

1. The combination with an internal combustion engine cylinder having both ends closed, of a piston working therein and dividing the cylinder into a combustion chamber and an induction chamber the induction chamber having a plurality of induction ports formed into its wall, a plurality of valves arranged and adapted to open the induction ports in accordance with separated piston cycles, a by-pass formed in the cylinder wall and adapted to open communication between the induction chamber and the combustion chamber only at the outer end of the piston stroke, a source of fuel supply for the valves and induction chamber, and independent throttles for said valves. 5
2. The combination with an internal combustion engine cylinder having both ends closed, of a piston working therein and dividing the cylinder into a combustion chamber and an induction chamber the induction chamber having a plurality of induction ports formed in its wall, an exhaust valve 10 working in the head of the combustion chamber, a plurality of valves arranged and adapted to open the induction ports in accordance with separated piston cycles, a by-pass formed in the cylinder wall and adapted to open communication between the induction chamber and the combustion chamber only at the outer end of the piston stroke, a source of fuel supply for the valves and induction chamber, and independent throttles for said valves. 15
3. An internal combustion engine provided with mechanism for changing its cycle of operation, said mechanism comprising two intake valves alternately opening communication with the engine on alternate piston cycles, and dual devices coöperative therewith for controlling flow of fuel to said valves. 20
4. An internal combustion engine provided with mechanism for changing its cycle of operation, said mechanism comprising two intake valves alternately opening communication with the engine on alternate piston cycles, and dual throttle controlled devices coöperative therewith for controlling flow of fuel to said valves. 25
5. An internal combustion engine provided with mechanism for changing its cycle of operation, said mechanism comprising two intake valves alternately opening communication with the engine on alternate piston cycles, and dual carbureters provided with throttles coöperative therewith for controlling flow of fuel to said valves. 30
6. An internal combustion engine provided with mechanism for changing its cycle of operation, said mechanism comprising two intake valves alternately opening communication with the engine on alternate piston cycles, dual carbureters provided with throttles coöperative therewith for controlling flow of fuel to said valves. 35
7. An internal combustion engine provided with mechanism for changing its cycle of operation, said mechanism comprising two intake valves alternately opening communication with the engine on alternate piston cycles, dual carbureters provided with throttles coöperative therewith for controlling flow of fuel to said valves, and means for selectively operating said carbureters. 40
8. An internal combustion engine provided with mechanism for changing its cycle of operation, said mechanism comprising two intake valves alternately opening communication with the engine on alternate piston cycles, dual carbureters provided with throttles coöperative therewith for controlling flow of fuel to said valves, and a pair of levers and operating connections for selectively operating the carbureters. 45
9. An internal combustion engine provided with mechanism for changing its cycle of operation, said mechanism comprising two intake valves alternately opening communication with the engine on alternate piston cycles, dual carbureters provided with throttles coöperative therewith for controlling flow of fuel to said valves and operating connections and a pair of levers mounted in juxtaposition for selectively operating the carbureters. 50
10. An internal combustion engine provided with mechanism for changing its cycle of operation, said mechanism comprising two intake valves inbuilt with the engine and alternately opening communication with the engine on alternate piston cycles, and dual devices coöperative with the valves for controlling flow of fuel to said valves. 55
11. An internal combustion engine provided with mechanism for changing its cycle of operation, said mechanism comprising two intake valves alternately opening communication with the engine on alternate piston cycles, and dual devices one on either side of the engine and coöperative therewith for controlling flow of fuel to said valves. 60
12. An internal combustion engine provided with mechanism for changing its cycle of operation, said mechanism comprising two rotary intake valves alternately opening communication with the engine on alternate piston cycles, and dual devices coöperative therewith for controlling flow of fuel to said valves. 65
13. An internal combustion engine provided with mechanism for changing its cycle of operation, said mechanism comprising two rotary intake valves one on either side of the engine and alternately opening communication with the engine on alternate piston cycles, dual carbureters provided with throttles coöperative therewith for controlling flow of fuel to said valves. 70

communication with the engine on alternate piston cycles, and dual devices coöperative therewith for controlling flow of fuel to said valves.

14. An internal combustion engine having separate combustion and induction chambers and provided with mechanism for changing its cycle of operation, said mechanism comprising two intake valves alternately opening communication with the induction chamber on alternate piston cycles, and dual devices coöperative therewith for controlling flow of fuel to said valves.

15. An internal combustion engine having a cylinder and piston working therein and dividing the engine into separate combustion and induction chambers and provided with mechanism for changing its cycle of operation, said mechanism comprising two intake valves alternately opening communica-

cation with the induction chamber on alternate piston cycles, and dual devices coöperative therewith for controlling flow of fuel to said valves.

16. An internal combustion engine having 25 a cylinder and piston working therein and dividing the engine into separate combustion and induction chambers and provided with mechanism for changing its cycle of operation, said mechanism comprising two 30 rotary intake valves one on either side of the induction chamber alternately opening communication with the induction chamber on alternate piston cycles, and dual devices 35 coöperative therewith for controlling flow of fuel to said valves.

In testimony whereof, I have signed my name to this specification.

SYDNEY I. PRESCOTT.
